UNITED STATES PATENT OFFICE.

ERASTUS G. OAKLEY, OF BRIDGEPORT, CONNECTICUT, ASSIGNOR TO BRIDGEPORT
BRASS COMPANY, OF BRIDGEPORT, CONNECTICUT.

TOWEL RACK OR LIKE FIXTURE.

Application filed October 19, 1921. Serial No. 508,641.

To all whom it may concern:

Be it known that I, ERASTUS G. OAKLEY, a citizen of the United States, residing in Bridgeport, county of Fairfield, and State of Connecticut, have invented certain new and useful Improvements in Towel Racks or like Fixtures, of which the following is a full, clear, and exact description.

My invention relates to towel racks or like fixtures, and more particularly to the provision of a firm and durable connection between a tubular member and a wall or base plate used therewith in the construction of wall fixtures of various kinds.

In the manufacture of many fixtures, it is common practice to secure the fixture by the provision of a wall or base plate generally disklike in form, to which is fastened a tubular or rodlike structure serving as a towel support or the like. It is desirable that the connection between this flanged base or wall plate and the stem or tubular structure, be one which may be formed economically and yet be rigid and strong, and neat in appearance.

One object of my invention is to simplify and cheapen the production of articles of the character described, while maintaining a high standard of quality.

Another object of my invention is to provide an improved method of securing a flange plate upon a rod or tubelike structure.

A still further object of my invention is the provision of an improved connection between the parts of a towel rack or like fixture, such that the parts may be rigidly and effectively secured together by a cheap and economical method.

To these and other ends the invention consists in the novel features and combinations of parts to be hereinafter described and claimed.

In the accompanying drawings:

Fig. 1 is a front elevational view of a towel rack embodying my improvements;

Fig. 2 is a top plan view of the same;

Fig. 3 is a detailed sectional view of my improved connecting means taken along line 3—3 of Fig. 1.

The preferred embodiment of my invention which I have selected to illustrate and describe comprises a towel rack or similar fixture consisting of a body 10 in the form

of a tube or rod upon the ends of which are 55 provided transversely extending flanges 11 and 12 in the form of base or wall plates manufactured separately from the tube or body 10 and thereafter secured thereon. These wall or base plates are adapted to be 60 secured to a suitable support by means of screws 13, or similar fastening members passing through perforations in the plates.

In order to provide a rigid and durable connection between each of the plates 11 and 12 and the body of the fixture 10, I form an annular, exterior shoulder 14 upon the body 10, adjacent each end thereof. In the case of a tubular body, such as is shown in the drawings, this shoulder is formed by distorting or flaring the wall of the tube outwardly and downwardly and then doubling it back upwardly and inwardly to form a substantially solid shoulder by the manifolding of the wall of the tube. The end of 70 the tube wall then continues in alignment with the body thereof without any change in its diameter. This shoulder may obviously be formed, if desired, by the mere outward distortion of the wall of the tube 75 without the wall being doubled back upon itself to form a substantially solid shoulder.

The wall or base plates 11 and 12 consist of members generally disklike in form projecting as flanges transversely from the body 10 of the fixture. The particular form or shape, however, of these members is not of importance as far as this invention is concerned. Each of the plates is provided with a centrally formed perforation 15, the 85 edge of which is turned axially of the tubular body 10 so as to provide an annular flange 16, which is adapted to lie flatly 90 against the tubular body when the latter is received in the perforation 15 of the plate. The outer surface of the plate may be lodged 95 against the shoulder 14 when the plate is slipped upon the end of the tube. The edge of the tubular body is then turned over and folded back, as at 17, upon the annular 100 flange 16 by a crimping or spinning operation in such a manner that the plate is lodged firmly against the shoulder 14 and gripped tightly between same and the turned over edge of the tube. The portions 105 16 and 17 of the plate and tube, respectively, form interlocking gripping knuckles, which constitute practical and durable connection

between the two parts in cooperation with the shoulder 14 against which the plate is clamped. In this operation the flange 16 may be slightly turned or deformed outwardly, so that a more effective gripping knuckle will be formed by it and the member 17.

It will be noted that, although the combination as above described is preferred, certain features may be omitted without impairing the usefulness and novelty residing in the remaining ones. For instance, it may be desirable to omit the flange 16 about the opening 15 in the plate member, in which case the connection between the plates 11 and the tubular member 10 would then consist only of the exterior shoulder 14 abutting against the upper surface of the plate member, and the upturned end of the tubular member abutting the under surface of the plate member. A secure and serviceable joint would thus be obtained, as the plate member would be held against slipping upwardly along the tubular member by the shoulder 14 and downwardly by the upturned end 17 being clamped therebetween. This in effect produces a structure having a plate member clamped between two shoulders formed upon a tubular member.

It will be obvious that the two parts of the fixture may be connected in this manner by machine work, which will be a relatively cheap operation and at the same time will hold the parts rigidly together without the use of rivets or solder, or similar fastening means.

It will, of course, be apparent that my invention will be capable of applications other than that shown in the embodiment herein described, and may be varied in details without departing from the spirit of the invention or the scope of the appended claims.

What I claim is:

1. In combination, a tubular member, an exterior shoulder provided thereon by reversely folding the wall thereof, and a plate member having an opening receiving said tubular member, and having an annular flange about the opening abutting the wall of the tubular member, the edge of the latter being spun over said flange to secure the members together with the surface of the plate member clamped tightly against the shoulder.

2. In combination, a tubular member having a shoulder formed externally thereon, and a second member secured thereto having a perforation receiving the end of said tubular member, but too small to receive said shoulder portion, the edge of the perforation in said second member being bent downwardly and interlocked with the edge of the tubular member by having the end of said tubular member spun over the downwardly

bent edge of the perforation in the second member to tightly grip the same and secure the two members together.

3. In combination, a tubular member having a shoulder thereon adjacent an end thereof and a base having a flanged opening therethrough, the end of said tubular member protruding through the flanged opening of said base and returned over the edge of the flange, whereby the tubular member and the base are securely connected together with the base clamped between the shoulder and the end of the tubular member.

4. In a towel rack or like fixture, a tubular member having its wall bent outward to form a shoulder thereon adjacent an end thereof, and a sheet metal base having an opening therethrough and an inwardly formed flange about the opening, the end of said tubular member protruding through the opening of said base and being returned over the edge of the flange whereby said member and base are secured together, and the front face of said base around said opening being thereby held in abutment with said shoulder.

5. In combination, a tubular member having a shoulder formed externally thereon, and a plate member, having a perforation therein, mounted upon said tube member with one surface thereof lodged against the shoulder and interlocking, gripping, annular flanges formed upon said plate member and tube to secure said parts in position.

6. In combination, a tubular member having its wall bent outward to form an exterior shoulder thereon adjacent its end, and a plate member provided with an opening whereby it embraces the end of said tubular member with the face of said plate member contacting with said shoulder, the edge of said opening comprising an annular flange bent away from said shoulder about and along said tubular member, the edge of the end of said tubular member being spun over and along said annular flange of the opening in said plate member for retaining said plate member upon said tubular member.

7. In combination, a tubular member having an exterior shoulder formed thereon, and a plate member having a hole therein fitting over an end of said tubular member against said shoulder, the edge of said opening being turned inwardly to form an annular flange, the end of said tubular member being spun over and upwardly about the inwardly turned flange of said plate member and pressing against the edge of the same to clamp said plate member against said exterior shoulder.

8. In a towel rack or like fixture, an article supporting bar having an exterior shoulder formed thereon adjacent an end thereof, and a base member provided with an opening to receive the end of said member and

having an inwardly directed flange about said opening, the end of said bar protruding through said opening and spun over the edge of said flange whereby said base is secured upon the end of said bar between said shoulder and said spun over end.

9. In an article support, an article supporting rod and a base member for said supporting rod, said base member provided with an opening and having an inwardly directed flange about said opening, one end of said rod for a predetermined distance along its

length being of proper cross section to be inserted into said opening in said base, while an adjacent portion of said rod is of too great a cross section for such insertion, said rod end protruding through said base in the opening thereof and having its ends spun over the edge of said flange whereby said base and rod are secured together. 20

In witness whereof, I hereunto set my hand on the 17 day of October, 1921.

ERASTUS G. OAKLEY.
